Primary Examiner — Marianne N Pandozzi

(57) **CLAIM**

The ornamental design for a skull with projectile, as shown and described.

DESCRIPTION

FIG. 1 is a front perspective view of a skull with projectile showing my new design;

FIG. 2 is a rear elevational view thereof;

FIG. 3 is a left side elevational view thereof;

FIG. 4 is a right side elevational view thereof;

FIG. 5 is a top plan view thereof;

FIG. 6 is a bottom plan view thereof; and,

FIG. 7 is a top plan view thereof;

FIG. 8 is a bottom plan view thereof;

FIG. 9 is a front perspective view of a skull with projectile showing a second embodiment of my new design;

FIG. 10 is a rear perspective view thereof;

FIG. 11 is a front elevation view thereof;

FIG. 12 is a rear elevation view thereof;

FIG. 13 is a right side elevation view thereof;

FIG. 14 is a left side elevation view thereof;

FIG. 15 is a top plan view thereof; and,

FIG. 16 is a bottom plan view thereof.

The broken lines in the drawing depict portions of the pirate mug that form no part of the claimed design.

1 Claim, 8 Drawing Sheets
